UNITED STATES PATENT OFFICE.

ELLA MARTIN, OF BOTTESFORD, ENGLAND.

SPARKING PLUG.

Application filed May 15, 1923. Serial No. 639,080.

To all whom it may concern:

Be it known that I, ELLA MARTIN, a subject of the United Kingdom of Great Britain and Ireland, and resident at Vine Cottage, Bottesford, in the county of Nottingham, England, have invented certain new and useful Improvements in Sparking Plugs, of which the following is a specification.

- 10 This invention relates to improvements in sparking plugs whereby the plug may be quickly and easily removed from the cylinder without breaking the electrical connections, so that the spark may be inspected
 15 in a fraction of the time now taken to break the electrical connections, unscrew the plug, and remake the connections. Further the construction of the sparking plug facilitates the renewal of damaged parts, and the ease
 20 with which the plug is removed from the cylinder renders it unnecessary to provide any other opening for priming.

The ordinary sparking plug consists of an insulated high tension electrode fixed in a holder, which screws into a hole in the engine cylinder, and from which the other electrode projects. The disadvantages of this type are that the electrical connection has to be broken before the plug can be unscrewed, the unscrewing takes time, the electrical connection has to be remade before the spark can be tested, it is difficult to find a resting place for the plug where the spark can be seen without the high tension terminal touching any conductor, and if the plug falls the spark electrodes are liable to be bent and the insulation to be broken.

According to this invention I employ a sparking plug which, instead of screwing, slides in and out of a hole in the engine cylinder, and is attached thereto in such a way that the electrical connections are not broken and the plug will not fall. As the ordinary engine cylinder is not provided with a suitable hole, or with a suitable place for the attachment of the plug when out of the hole, I generally prefer to attach the plug to a bush screwing into the hole provided for the ordinary sparking plug. When the engine is working the sparking plug must make a tight joint with the cylinder and for this purpose the attachment of the plug is provided with a screw or lever device which will press the plug into the hole and hold it firmly until released. In order that this pressure may be applied from above with-

out the attachment therefor either coming too near the high tension terminal or occupying too much space I make the plug with a right angle bend so that the terminal 60 comes out at the side.

It will be obvious that the plug, being separate from the screwed bush, will be a smaller and cheaper thing to replace than the ordinary sparking plug, but I may make 65 the high tension electrode detachable from the insulator, and the insulator from the holder, so that any part of the plug can be replaced.

In the drawings, illustrating what I now 70 consider a preferred embodiment of my invention, Fig. 1 is a side view, and Fig. 2 is a section taken on the line 2—2 of Fig. 1.

In the drawing A is the plug which slides into the screwed bush B and makes a tight 75 joint therewith when the shoulder *m* is pressed against the washer *w*. This pressure is produced by the screw *s* which is turned by the handle *h* and passes through a nut *v* pivoted at *v* to the link *k*. Intermediate the bush B and the plug A are rings *B*¹ and *B*², which are provided to make a swivel connection so that the plug A may be opened in any convenient position. The link *k* is pivoted to the screwed ring *B*¹ so that when the plug A is in position the screw *s* can press on the upper part *u* and make a tight joint between the shoulder *m* and the washer *w*. This is possible because the plug is made with a right angle 85 bend so that the high tension terminal *t* comes out at the side through an extension *i* of the insulating material.

As shown in Fig. 2, the bush B is provided with an external thread at its upper 90 end to receive the flanged ring *B*². It is also counter-bored to receive a flanged tubular member *B*³, which swivels the ring *B*¹ on the bush B in a manner readily understood. Suitable packing rings *x*, *y*, *z*, may 100 be provided as shown.

What I claim as my invention and desire to secure by Letters Patent is:—

The combination of a sparking plug having a right angle bend, a link for attaching the plug to a ring adapted to swivel on a bush fitting in a threaded hole in the engine, and a screw for making a tight joint 105 between the plug and the bush.

In witness whereof I affix my signature.

ELLA MARTIN.
